Primary Examiner — Keli L Hill

(57) **CLAIM**

The ornamental design for a beverage bottle, as shown and described.

DESCRIPTION

1.-2. Beverage bottle

1.1: Front

1.2: Back

1.3: Right

1.4: Left

1.5: Top

1.6: Bottom

1.7: Reference view

1.8: Cross-sectional

1.9: Cross-sectional

2.1: Front

2.2: Back

2.3: Right

2.4: Left

2.5: Top

2.6: Bottom

2.7: Reference view

2.8: Cross-sectional

2.9: Cross-sectional

The broken lines illustrate structure or features form no part of the claimed design.

Reproductions Nos. 1.7 and 2.7 are reference views indicating the state without a cap; reproductions Nos. 1.8 and 2.8 are cross-sectional views cut vertically at the diagonal lines of the top views; reproductions Nos. 1.9 and 2.9 are cross-sectional views cut horizontally at the centers of the front views.

1 Claim, 18 Drawing Sheets
